January 2, 1948

4 Claims. (Cl. 60—39.65)

1

This invention relates to improvements in combustion systems, and is intended to be more particularly applicable for use with pulverulent solid fuel or heavy fuel oil.

It is known in order to facilitate the combustion of finely divided solid fuel in a fluid, to impart a vortex motion to this fluid, and to introduce the solid material into some part of the vortex.

A system is also known from British Patent No. 338,108 for carrying out chemical and physical processes involving interaction between fluids or between finely divided solid material and fluids, for instance, the combustion of finely divided solid fuels, in which vortex motion is imparted to a fluid, and the material between which and the said fluid interaction is to be secured is introduced into some part of the vortex in such a way that the material is suspended with either no radial velocity or comparatively low radial velocity relative to the axis of the vortex and so that the equilibrium paths of the particles of the material under the combined action of centrifugal forces and forces tending to move them towards the axis of the vortex are within the chamber in which the vortex is produced, while the fluid has a comparatively high velocity relative to the axis so as to obtain relative radial motion between the fluid and the material. Further, in accordance with this system the conditions with respect to the speed of the fluid in the vortex and the physical properties of the material introduced thereto are so related that as the reaction proceeds the material will progressively move towards the axis of the vortex; this movement occurs as the particles shrink during the reaction and take up an equilibrium path nearer the axis.

A combustion system of the character described (in the last preceding paragraph) does not in itself provide a flow pattern suitable for use in cases in which combustion has to be supported by a fast moving stream of fluid (hereinafter considered as being air), and an object of the invention is to adapt a system of the said character to the requirements of such cases. The description "fast moving" as applied to a combustion-supporting air stream is intended herein to indicate that the mean speed of the air stream in its general direction of flow past a combustion initiating zone, calculated from the ratio air volume passing in unit time/cross sectional area of the flow path, is sufficiently high in relation to the speed of flame propagation in the fuel-air mixture concerned to have flame extinguishing properties. For hydrocarbon fuels burning in air the speed of flame

2

propagation is considered as being of the order of one foot per second at a atmospheric temperature; the invention, on the other hand, is especially applicable to combustion apparatus for internal combustion gas turbine and/or jet propulsion power units in which the speed of the air stream in its general direction of flow past a combustion zone, calculated on the basis indicated, might be from 10 to 300 feet per second or even more, depending on the design. The invention is further of particular interest in relation to installations which, in common with such power units, require stabilised burning to be supported not only by a fast moving air stream but also with high air/fuel ratios, and in which stable burning is required to be maintained at high rates of fuel injection with a minimum of pressure loss.

According to the invention, in a combustion system of the character described in which combustion has to be supported by a fast moving air-stream means are provided for stabilising the flame produced by the combustion of the fuel.

A further feature of the invention is based on the fact that the velocities and paths of the particles in the vortex chamber are determined largely by the form of the boundary walls, because the radial velocity component of the gas at any particular radial distance from the axis of the vortex depends on the cross-sectional area available for radial flow at the radial distance. Any desired movement of these particles can thus be ensured by suitable design of the chamber walls and by suitable operating conditions.

Dynamical investigation has shown that certain arrangements have a favourable effect on flow stability and pressure loss. It is in the first place desirable that the radial velocity component of the gas should be either constant, or should vary continuously from entry to outlet with varying radial distance from the axis of the vortex; with the object, according to a further feature of the invention the vortex chamber is defined by boundary walls having a form such that the distance between a point on one wall and a corresponding oppositely located point on the opposite wall measured in the direction of the axis varies continuously from the periphery up to the outlet with varying radial distance of the points from this axis and is greater at smaller radii.

Preferably the form of the boundary walls defining the vortex chamber is such that the said axial distance between opposite walls is substantially an exponential function of the said radial distance, and conveniently the boundary walls are generally outwardly concave form. (In this

context "outwardly" concave or convex means as viewed externally.) A particular case which may have certain advantages for example in respect of pressure loss occurs when the said function is hyperbolic in which case the radial velocity component will be substantially constant at all radii.

In the use of liquid fuels of low volatility, difficulties are often encountered owing to the wide range in the sizes of the droplets produced by the pressure operated jet or air blast atomiser which is generally employed.

A further difficulty is that in the case of some crude liquid fuels the viscosity varies over a wide range for comparatively small changes in temperature, thus substantially altering the degree of atomisation and thence the combustion performance.

With the object of avoiding these disadvantages according to a still further feature of the invention the vortex combustion chamber is provided with centrifugal means adapted to introduce fuel particles with a movement of rotation about the axis of the chamber.

By way of example, an embodiment of the invention is described below with reference to the accompanying drawings in which:

Figure 1 is a transverse section of said embodiment and;

Figure 2 is a section on the line II-II of Figure 1.

Referring to Figure 1, the combustion apparatus comprises a flame tube enclosed by a duct 24 into which is passed a fast moving air stream, as for example, the delivery from the air compressor of a gas turbine engine, and a combustion chamber generally indicated at 4 into which the duct 24 and the flame tube enclosed thereby lead.

The flame tube is generally similar to that described in co-pending United States patent application Serial No. 250,701 in the name of Lloyd, filed October 10, 1951, which is a division of the present application. It comprises a tubular duct 25 which divides the stream entering the duct 24 into two portions, one portion constituting secondary air and passing into the annular space 17a between the two ducts, and the other portion constituting primary air and passing into the interior of the duct 25. The second portion is further divided into two parts by a further tubular duct 26 supported coaxially within duct 25 by a spider 29 at one end and swirl vanes 25a at the other end. One part of the air passes through the annular space between ducts 25 and 26 and is given a swirling motion about the axis 7 of the ducts by the swirl vanes 25a. The other part flows partly through the swirl vanes 23a and partly through apertures 27a in a cup shaped stabilising baffle 27.

Mounted centrally in the flame tube is an air blast burner 23 for crude liquid fuel, the term "air blast burner" meaning in this case a burner in which atomisation of the liquid fuel is effected by means of an air blast. In the burner shown, liquid fuel is led through pipe 21 while compressed air is led through pipe 22 in order to atomise the fuel.

The stabilising baffle 27 forms on its downstream side a stabilised combustion zone into which the fuel is injected and where it is ignited by means of spark plug 31. The ignited fuel particles are carried by the swirling air 3 into the combustion chamber 4. It will be appreciated that on entering the combustion chamber, the stream tends, due to its swirling movement, to

fly outwards towards the peripheral part of the chamber and will carry with it the burning particles of fuel.

The first portion of the air stream entering duct 24 flows into the annular space 17a between the ducts 24 and 25. The duct 25 merges into one side wall 4d of the chamber 4, and the duct 24 into a wall 4e spaced from the wall 4d. The air flows between these two walls through a series of swirl vanes 28 arranged as shown in Figure 2 to swirl the air about the axis 7. Part of this air enters the combustion chamber 4 as secondary air through peripheral inlets 19 which are provided with swirl vanes 19a which accordingly define tangential inlets. The swirl vanes 28 and 19a thus give the air a vortex motion about the axis 7.

Within the chamber 4 the gases circulate around the axis 7 in vortex manner, the fuel particles, which are initially carried outwards by the swirling air stream from the flame tube, moving in a circular path and slowly approaching the axis while being burnt until they are either completely burnt or until a very fine ash residue remains which passes together with the combustion products through the axial outlet 8 formed in the wall 4f of the combustion chamber 4.

The air flowing through the space 17a between the walls 4d and 4e serves to cool the combustion chamber walls 4d. Part of this air does not enter the chamber 4 but flows through the space 17b between the wall 4f of the combustion chamber and the outer walls 4k, 4g and 4h, thereby cooling wall 4f. This air finally passes between swirl vanes 8a arranged in the vicinity of the outlet 8, and mixes with the combustion gases as tertiary air to act as a diluent and coolant.

We claim:

1. Combustion apparatus in which particles of solid or heavy liquid fuel are to be burnt in air supplied as a fast moving stream comprising a combustion chamber having two opposed coaxial side walls, one of which is formed with a central inlet for part of the stream, and the other with a central outlet, and means for admitting a further part of the stream peripherally into the chamber with a swirling motion about the axis thereof; an axial tubular extension from said central inlet in the first-mentioned side wall, affording a path leading to said inlet for said first-mentioned part of the stream; means for forming a stable zone of combustion within said extension; means for injecting fuel into said zone; and means for causing ignited fuel particles to be carried outwards from said zone into the peripheral part of the combustion chamber.

2. Combustion apparatus in which particles of solid or heavy liquid fuel are to be burnt in air supplied as a fast moving stream comprising a combustion chamber having two opposed coaxial side walls, one of which is formed with a central inlet for part of the stream, and the other with a central outlet, and means for admitting a further part of the stream peripherally into the chamber with a swirling motion about the axis thereof; an axial tubular extension from said central inlet in the first-mentioned side wall, affording a path leading to said inlet for said first-mentioned part of the stream; means for forming a stable zone of combustion within said extension; means for injecting fuel into said zone; and swirlers within said extension disposed to swirl the part of the air stream passing therethrough about the axis thereof, whereby ignited particles of fuel are picked up by the swirling air stream and

carried outwards from said zone into the peripheral part of the combustion chamber.

3. Combustion apparatus in which particles of solid or heavy liquid fuel are to be burnt in air supplied as a fast moving stream comprising a combustion chamber having two opposed coaxial side walls, one of which is formed with a central inlet for part of the stream, and the other with a central outlet, and means for admitting a further part of the stream peripherally into the chamber with a swirling motion about the axis thereof; an axial tubular extension from said central inlet in the first-mentioned side wall, affording a path leading to said inlet for said first-mentioned part of the stream; a further tubular member coaxially located within said extension and defining therewith an annular passage; means for forming a stable zone of combustion within said further tubular member; means for injecting fuel into said zone; and swirlers within said annular passage disposed to swirl the air passing therethrough about the axis thereof, whereby ignited particles of fuel are picked up by the swirling air stream and carried outwards from said zone into the peripheral part of the combustion chamber.

4. Combustion apparatus in which particles of solid or heavy liquid fuel are to be burnt in air supplied as a fast moving stream comprising a combustion chamber having two opposed coaxial side walls, one of which is formed with a central inlet for part of the stream, and the other with a central outlet, and means for admitting a further part of the stream peripherally into the chamber with a swirling motion about the

35

axis thereof; an axial tubular extension from said central inlet in the first-mentioned side wall, affording a path leading to said inlet for said first-mentioned part of the stream; a jacket spaced from said extension and from said side wall and defining therewith a path for said further part of the stream; a further tubular member coaxially located within said extension and defining therewith an annular passage; means for forming a stable zone of combustion within said further tubular member; means for injecting fuel into said zone; and swirlers within said annular passage disposed to swirl the air passing therethrough about the axis thereof, whereby ignited particles of fuel are picked up by the swirling air stream and carried outwards from said zone into the peripheral part of the combustion chamber.
